UNITED STATES PATENT OFFICE.

JACOB T. JOHNSON, OF ATLANTA, GEORGIA.

COMBINATION-HAMMER.

1,286,335.

Specification of Letters Patent.

Patented Dec. 3, 1918.

Application filed April 20, 1916. Serial No. 92,507.

To all whom it may concern:

Be it known that I, JACOB T. JOHNSON, a citizen of the United States, residing at Atlanta, in the county of Fulton and State of Georgia, have invented a new and useful Combination-Hammer, of which the following is a specification.

It is the object of this invention to provide a hammer which, in addition to possessing as incidental advantages, some of the features of a compound tool, will be so constructed as to prevent an undue bending of a nail, while the nail is being drawn, and also prevent a splintering of the material wherein the nail is held.

Figure 1 is a perspective showing one form of the invention; and Fig. 2 is a perspective showing a modification, parts being broken away.

As shown in Fig. 1, there is depicted a hammer comprising a head 1 and a handle 2 disposed at right angles to the head 1, the head 1 being provided, in alinement with the handle 2, with a prominent outstanding first finger 3, which may be a screw driver. The head 1 is provided at one end with a second finger 4 and with a bifurcated nail-pulling claw 5 disposed between the fingers 3 and 4, the claw 5 and the second finger 4 being curved toward the handle 2. The second finger 4 is longer than the claw 5, and the claw 5 projects beyond a line A—B tangent to the ends of the fingers 3 and 4, whereby the handle 2 may be swung in one direction thereby to elevate the claw 5 with a second finger 4 as a fulcrum, and then be swung in opposite direction with the first finger 3 as a fulcrum, in order to prevent

an undue bending of the nail and to prevent a splintering of the material wherein the nail is held.

In Fig. 2 of the drawings, parts hereinbefore described are designated by numerals previously used, with the suffix "a". The distinguishing characteristic of the structure shown in Fig. 2 is that the first finger 3^a is in the form of a claw.

Having thus described the invention, what is claimed as new is:

A hammer comprising a head and a handle disposed at right angles to the head, the head being provided, in alinement with the handle, with a prominent outstanding first finger, the head being provided at one end with a second finger and with a bifurcated nail-pulling claw disposed between the fingers, the claw and the second finger being curved toward the handle, the second finger being longer than the claw and the claw projecting beyond a line tangent to the ends of the fingers, whereby the handle may be swung in one direction thereby to elevate the claw with the second finger as a fulcrum and then be swung in an opposite direction with the first finger as a fulcrum, in order to prevent undue bending of a nail and to prevent a splintering of the material wherein the nail is held.

In testimony that I claim the foregoing as my own, I have hereto affixed my signature in the presence of two witnesses.

JACOB T. JOHNSON.

Witnesses:

R. B. CLARK,
F. C. HEDNALL.
